PANTS OR SIMILAR ARTICLES

Donal L. Bowcut, 111 S. George St.,
Charles Town, W. Va. 25414

Filed Feb. 22, 1972, Ser. No. 228,474

Term of patent 14 years

Int. Cl. D2—02

U.S. Cl. D2—28

FIG. 1 is a front perspective view of pants showing my new design in opened position;

FIG. 2 is a rear perspective view thereof; and

FIG. 3 is a front elevational view of a second embodiment of the design of FIG. 1 shown on a smaller scale.

I claim:

The ornamental design for pants or similar articles, substantially as shown and described.
